INDICATOR

Lyman E. Dodge, Morris Township, Morris County, N. J., assignor to Frank C. La Mar, Tucson, Ariz.

Application June 27, 1936, Serial No. 87,643

4 Claims. (Cl. 200—121)

This invention relates to electrical fuse devices, especially to integrity indicator means for cartridge type fuses, and more particularly to the class of such integrity indicators in which the indicator device is formed as a unitary structure having an entity distinct from that of the cartridge fuse or other type of fuse with which the indicator device is intended to be assembled in use.

10 An outstanding object of the present invention is to provide a means by which it is possible to have the integrity indicator so conjoined with the fuse cartridge supporting structure, when in use, that the indicator will not be displaced by the vibrations and shocks encountered ordinarily in the use of such protective devices, also to provide that the integrity indicator shall be so disposed with relation to the fuse cartridge that its presence will not interfere at all with manipulation 20 of the fuse cartridge during inspections, adjustments and renewals thereof, but that, on the contrary, the fuse cartridge, and the integrity indicator, shall each be capable of removal and replacement independently of the other. By this means the invention avoids the chance of mislaying the indicator, losing, or forgetting to put it back, and so leaving the fuse without an integrity indicator.

Among other requirements which are desirably 30 to be satisfied by a fuse-integrity indicator intended for assembly with a cartridge type fuse, and to provide for which is the general object of the present invention, is the need that the indicator device shall be capable of assembly 35 readily with, and attachment to, the structure which serves to support the fuse cartridge, being provided with electrical terminals by which the fuse is contacted and thereby included in the working circuit to be protected; also that such an 40 integrity indicator shall be adaptable for use with cartridge fuses of generally standard sizes and types, though differing in non-essential details; also that the adaptation of the indicator to a given type of fuse can be effected without alteration 45 in the structure of the fuse cartridge by a user, and that if any alteration of the fuse cartridge, or of the integrity indicator, must be made by the manufacturer, in adapting the indicator to one or another make of fuse cartridge, such 50 alteration shall be of an inconsiderable character, and may be performed at the manufactory instead of at the place of installation of the cartridge fuse and indicator.

Many of the integrity indicators at present applied to cartridge fuse assemblies for the afore-

said purpose, fail to satisfy the foregoing requirements in many respects, and none of such indicators are to be regarded as meeting all of the requirements in a completely satisfactory manner.

5 Among the outstanding deficiencies that have been characteristic of some of the fuse-integrity-indicators now on the market, may be mentioned the tendency to shake away from the cartridge and fall into positions where they cause shorts, 10 or crosses, in the electrical working circuit sought to be protected by the fuse, and the integrity or condition of which is desirably to be indicated reliably at all times; also the tendency to become loose to such an extent that the electrical 15 contact is impaired, or broken, even if the indicator is apparently in place and operatively connected; a defect which is particularly dangerous for the reason that a defective circuit condition may exist without being signalled, the normal 20 appearance of the indicator being deceptive.

Other objects and advantages will appear as the description of the particular physical embodiment selected to illustrate the invention progresses, and the novel features will be particularly pointed out in the appended claims.

In describing the invention in detail and the particular physical embodiment selected to illustrate the invention, reference will be had to the accompanying drawings and the several views 30 thereon, in which like characters of reference designate like parts throughout the several views, and in which:

Figure 1 is a view in side elevation, partly in section, or a protective device for electrical circuits, in which a fuse cartridge element is shown in assembly with a support and with an integrity indicator element, the supporting structure and associated connections being shown partly in section; Fig. 2 is a view in end elevation of the assembly illustrated in Fig. 1; Fig. 3 is a fragmentary detail view in plan of certain parts shown in Fig. 1, with the cover of the indicator removed; Fig. 4 is a horizontal sectional view similar to Fig. 3 but with the indicator lamp omitted, to reveal the support therefor; Fig. 5 is a detail view in perspective of the supporting bracket for the indicator element shown in Fig. 1, but the bracket being shown separately; Fig. 6 is a similar perspective view in detail of another bracket shown 40 at the right hand of Fig. 1, the bracket being taken separately; Fig. 7 is a view in side elevation similar to Fig. 1, but illustrating a modification; Fig. 8 is a fragmentary detail view of the supporting base shown in Fig. 7, but with a modified dis- 50 55

position of the conductor which completes the indicator shunt; Fig. 9 is a fragmentary detail view in side elevation, partly in section, of another modification of the integrity indicator element and its associated parts; Fig. 10 is a fragmentary, detail view in end elevation, partly in section, of still another modification of integrity indicator and associated parts; Fig. 11 is a view in plan of the parts as shown in Fig. 10; Fig. 12 is a detail view in perspective, on a greatly enlarged scale, of the indicator-lamp-bracket and a resistance element, associated in a unitary structure separately from the base of the protective device; Fig. 13 is a fragmentary, detail view of the indicator lamp as in Fig. 10, but illustrating a protector shield for the lamp, the view being taken on a larger scale; Fig. 14 is a view in horizontal section on the line 14—14 of Fig. 13; Fig. 15 is a view in perspective of a modified form of shield; Fig. 16 is a view in horizontal section, taken on the line 16—16 of Fig. 15; Fig. 17 is a view in side elevation illustrating an assembly of a modified form of integrity indicator element with a cartridge fuse element, mounted on a supporting base of which a part only is shown, in section; Fig. 18 is a view in end elevation of the structure shown in Fig. 17; Fig. 19 is a plan view of the structure as shown in Figs. 17 and 18; Fig. 20 is a view in side elevation of another modified form of integrity indicator element in assembly with a fuse cartridge element mounted upon a supporting base; Fig. 21 is a plan view of the structure shown in Fig. 20, showing in horizontal longitudinal section an adjustable shunt connection forming part of the structure; Fig. 22 is a fragmentary detail view of a modified form of adjustable electrical shunt connector including an integrity indicator element adapted to be assembled with a fuse cartridge element; Fig. 23 is a view in end elevation of another modified form of integrity indicator element and supporting means therefor, in assembly with a fuse cartridge element; Fig. 24 is a view in side elevation of still another modified form of integrity indicator with a swinging support, and shown in assembly with a terminal of the electrical circuit to be protected; Fig. 25 is a view in rear elevation of the structure shown in Fig. 24.

In a now-preferred embodiment of the invention selected for illustration and description, referring first to the structure shown in Figs. 1 to 5, inclusive, the part designated by the reference character F is a fuse cartridge of the conventional ferrule type, mounted in clips C'C'' made of sheet metal, and which embrace a ferrule 10 at one end of the fuse cartridge and a ferrule 11 at the other end thereof, the ferrules constituting the end terminals of a fusible element 12 confined within a barrel 13 of insulating material.

The feet 16 of the clips are secured to the base B by screws 18 which transfix also metal straps 17 extending outwardly toward each end, where binding screws 21 and 22 are provided to serve as terminals by which the fuse cartridge element may be included in series in the electrical working circuit to be protected.

Each binding screw 21, 22 serves to hold down also the foot, as 19, 20, of one of a pair of brackets B' and B'', there being one bracket adjacent each end of the fuse cartridge, and each so disposed as to cause no interference by the brackets with ready removal of the fuse cartridge F, at will, independently of the indicator element.

The bracket B', in further pursuance of the invention, serves as a support for the integrity indicator element, designated generally by the

reference character I, and which comprises, in the instance illustrated in Figs. 1 to 3, a lamp N of the neon-filled discharge type, enclosed in a casing 23, the lamp being visible through an orifice 24 (see Fig. 2).

As shown in Fig. 3, in which the cover of casing 23 is omitted, the lamp is provided with the usual terminals 25 and 26 of which the first-named is connected to one end of a resistance R, preferably of the order of 50,000 ohms to 100,000 ohms, from the other end of which a conductor 27 runs, through an orifice 28 in the bottom of the casing 23, to a terminal stud 31 extending from the base 23x of casing 23 and adapted to enter a complementary keyhole slot 29 in a bracket lug 33, best seen in Figs. 4 and 5, another keyhole slot 30 therein serving to cooperate with a stud 32 also provided at the base of the casing 23, as shown in Fig. 2.

When thus mounted, the indicator element I is securely held, entirely out of the way of the fuse indicator element F, and each of said elements may be removed while the other remains in place, or each may be tested, inspected and adjusted without disturbing the other.

In the structure shown in Figs. 1 and 3, one terminal, as 26, of the indicator means, the indicator being in this instance the neon discharge lamp N, is extended by an insulated conductor portion 26' to be connected with the bracket B' at the other end of the fuse cartridge element F, for the purpose of completing the shunt around the element F as already described.

As shown in Fig. 6, the bracket B' has a foot 20 with an open slot 20' and lugs 39 to aid in maintaining alignment of the foot upon the underlying strap 17. It has also an upright post 20x with a bracket part 23x bent over in parallelism with the foot and having an eye 30' adapted to receive the bared end 26x of conductor 26' as illustrated in Fig. 1. The latter is wedged firmly in a slit 30'' but may be detached readily therefrom when it is desired to remove the fuse cartridge F or the integrity indicator I. When the removal of the indicator is not necessary, the conductor is simply drawn out of the slot 30'', and from the eye 30', and remains connected with the indicator, the latter retaining its established position on the other bracket B'.

In the modification illustrated in Fig. 7, the bracket B' and integrity indicator I supported thereby remain as shown in Fig. 1, but the bracket B'' is omitted, and the conductor 26'' is led down along the cavity 17x in the base B to an electrical connection with an eye or eyes 30'' formed on the spring clip member C''. The conductor 26'' is led down through orifices 34 and 35 formed in the upper and lower beads (see Fig. 5) which join the post of the bracket B' to the foot 19 thereof, and to the bracket part 33 thereof.

An open slot 40 permits the foot 19 to be slipped under the binding terminal screw 21, which transfixes the underlying strap 17 by which current is led to fuse clip C', the foot 16 of the clip being transfixated by the screw 18, which secures the foot and strap to the base.

In the modification illustrated in Fig. 8, the conductor 26³ is led from the indicator element, just as is the conductor 26'' (shown in Fig. 7), down through orifices 34 and 35 and through an orifice 43 which is formed in the base B near the foot 19. In the lower face of the base, a channel 44 is provided, leading past the head 18' of screw 18, to the recess 46 which receives the head 18'' 75

of the screw 18 which secures the strap 17'' (see Fig. 7) to the base, and the conductor 26³ is thereby so disposed as to complete the shunt circuit for the lamp N, around the fuse.

5 It will be understood of course that the recess 45 containing the head 18' of the screw 18 is sufficiently deep to enable the insulated conductor 26³ to clear the screw-head 18', and it is also clear that in this instance, where the shunt conductor 10 is led below the base, as well as in the instance shown in Fig. 7 where the conductor is led through the cavity 17x, the removal of the fuse cartridge may be accomplished without disturbing the integrity indicator and its connections, so 15 that these illustrative examples of physical embodiments of the present invention have in common the desirable provision for maintaining the integrity indicator in its established position at all times (except when it must be itself replaced), 20 and there is accordingly no danger that it will be lost, misplaced or forgotten, when the fuse cartridge is removed, an operation which occurs naturally more frequently than a similar replacement of the integrity indicator structure.

25 It is also to be noted that when the indicator means I is removed, for any reason, it is not necessary to remove the bracket B', and its connections with the terminal strap 17' can be maintained as originally established, a notable advantage, as it assures the continuance of good electrical connections at that point in the circuit. The provision of an orifice 47 in the bracket part 33 makes it possible to reach the head 21 of the binding screw readily with a screw driver, so that 35 the screw can be tightened, or loosened, whenever necessary after removal of the indicator means I.

Inasmuch as the axis of movement of the indicating means I, when being removed by shifting the studs 33 toward the larger orifices of the 40 keyholes 29 and 30 (see Fig. 4) is at right angles to the general trend of the insulated conductor 26' or 26'' or 26³, as the case may be, it is possible to free the indicating means from its bracket in each of the forms above described, without 45 disconnecting the conductor at its end remote from the lamp, and as the conductor is preferably an integral extension of the lamp terminal, or permanently connected therewith by some form of metallic union, the easily attachable-detachable connection of the indicator means to its bracket does not interpose any difficulty in the 50 way of its removal for any purpose, including that of gaining access to the binding screw 21.

In Fig. 9, a modification is shown in which the 55 above desirable capacity for easily attachable-detachable assembly of the indicator means I is provided, with a somewhat different disposition of the bracket part 50 upon which the indicator device I is mounted, this part having the same 60 form of complementary studs 33 and keyhole slots 29 and 30 shown in the preceding figures and described with reference thereto. The variation consists in arranging the keyhole slots so that, as indicated in Fig. 9, the studs 33 are disposed in a 65 line parallel with the length of the cartridge fuse F⁹. Thus, the indicator means I will be shifted manually along that line, for purposes of attachment and detachment, relatively to the bracket part 50 of bracket B⁹ and the insulated conductor 26³ serves the same purpose, and is 70 similarly disposed to complete the shunt around the cartridge fuse F⁹ so that it will not be necessary to repeat that part of the description covering this feature.

75 This disposition of the bracket part 50, with

its stud and keyhole slot connection arranged coaxially of the protective device, may of course be utilized with various forms of cartridge fuse, indicator means, fuse-cartridge and supporting structure. In the present instance the fuse cartridge F⁹ is of the known knife-blade type, having at each end a tang like that shown at T projecting beyond a metal cap 51 screwed on a ferrule 52, and connected with the fusible element 12 confined within the barrel 11 of the cartridge.

Each end tang T is held in clips 53 of known form, and the bracket B⁹ consists of an angle piece of sheet metal having an attachment part 54, with a slot (not shown) enabling the slotted part 54 to fit upon the tang T and be embraced between the clips 53 and the screw cap 51, making therewith a good electrical connection which is enhanced by the rubbing action of the contiguous edge of the cap if the latter happens to 20 become loose.

The bracket part 50 has already been described, but it is to be noted that in the event that it is desired to remove the fuse cartridge F⁹, it is possible to shift the indicator means I 25 readily in an inward direction and then to tilt it out of the keyholes in bracket part 50, leaving the indicating lamp with its casing 55 still attached by conductor 26³ to the binding screw 56, so that when desired the indicator I can be re- 30 stored by simply reversing the direction of shifting just described, no binding screw connections having been impaired.

The bracket B⁹ will accompany the fuse cartridge F⁹ when the latter is removed from clips 35 53, and may be slipped off the tang T in order to clear the cap 51 for the unscrewing operation necessary to permit withdrawal and replacement of the fusible element 12.

This form of device has the advantage under 40 certain conditions that the indicator element as such is readily detachable from the removable fuse cartridge, but need not be wholly disconnected from the circuit.

In Figs. 10 to 12 is shown a modification of the 45 invention, which illustrates an integrity indicator element I¹⁰ of very compact construction, comprising a suitable indicator lamp N' such as a neon-filled discharge lamp, having a threaded metal sleeve 59 connected in known fashion 50 with an interior terminal of the lamp and screwed into a metal socket 60 forming part of a bracket which is best shown in Fig. 12, being there designated generally by the reference character B¹². A strap 61 connects the lamp socket 55 60 electrically with one end of a suitable resistance R spaced from the socket by cup-shaped insulation 62, the other end of the resistance being in electrical connection, as at 64, with a bracket part 65 extending laterally from a post 60 67 which is bent up from a foot 66 of the bracket the foot being suitably slotted, as at 71 to be fitted under a binding screw 68 (see Figs. 10 and 11) which serves as an end terminal by which the fuse cartridge element F¹⁰ may be included 65 in the electrical circuit to be protected. The cartridge shown is, for illustrative purposes merely, of the ferrule type, having an end member 70 embraced by spring clips 71 extending upward from the foot 69.

70 There is a similar clip and binding screw at the other end of the fuse cartridge structure (not shown) and in order to complete the shunt in which the indicator means I¹⁰ is included, relatively to the fuse cartridge F¹⁰ whose condi- 75

- tion is to be indicated thereby, a conductor 72 is provided, one bare end of which may desirably be riveted as at 73, into the insulating cup 62 in position to be contacted by the usual central base 5 stud at the bottom of lamp N', and this contact is accordingly insulated in known manner from the metal lamp socket 60. The insulated conductor 72 is extended to, and connected with, the binding screw or some electrically associated 10 part at the other end of the fuse supporting structure (not shown).

By reference to Fig. 11, it will be seen that when the foot 66 of the bracket B¹² is slipped under the binding screw 68, the upright bracket 15 post 67 is disposed at the side of the cavity 74 in the end 75 of the base B, having the binding screw 68 free for access at all times.

The fuse cartridge element F¹⁰ can be removed independently of the entire integrity indicator 20 element I¹⁰ at any time, and the indicator element can be applied, as an entity, to existing fuse cartridge assemblies and can be removed therefrom, without essential alteration of the structure. The indicating means, in this instance the 25 lamp N' can be unscrewed from its socket and replaced by a fresh lamp, without the use of tools, and without disturbance of any other electrical connection.

The whole integrity indicator element occurs 30 a space at the end of the fuse cartridge assembly which is ordinarily waste space, and the upstanding character of the indicator lamp constitutes it a very visible and attention-arresting means to signal the circuit condition, when 35 energized by flow therethrough of an adequate current in the shunt, upon fusion of the fusible element in the fuse cartridge F¹⁰, in known manner.

Under certain conditions, it may be desirable 40 to provide protection for this lamp against mechanical contacts apt to be encountered in particular installations, and for this purpose the drawings illustrate different illustrative forms of shields.

That shown in Fig. 13 at 80 may be briefly designated as a pulpit-type shield, having a ring-shaped base 81 which surrounds the lamp socket 82 and resistance R, these latter parts corresponding preferably to those described with reference 50 to Figs. 10 to 12 and which are shown in detail in Fig. 12.

In Figs. 15 and 16, a shield 85 is shown, of a type which is designed to fit over the lamp N' without extending downward over the socket 55 parts, upon which the shield is seated. This shield has a waist 86 sufficiently constricted to afford an easy grip for the digits of an operator's hand in manipulation of the shield, an orifice 87 being provided in the waist at each side thereof, 60 and another orifice 88 in the end, through all of which orifices the light of the lamp will escape when it is energized, in the manner already described.

In the modification of the invention illustrated 65 in Figs. 17, 18 and 19, the part designated by the reference character F¹⁷ is a cartridge fuse element of known type, having a barrel 11 enclosing a fusible element (not shown) in electrical connection with metal end caps or terminals 13 70 and 14 by which the cartridge fuse is held in a pair of spaced clips C' and C'', the feet 16 (see Fig. 18) of which are secured to base B¹⁶ by suitable means, such as the screw 18 indicated by dotted lines. Beyond the clips C' and C'' respectively, similar clips C³ and C⁴ are provided,

in electrical connection with the first named pair of clips and preferably integrally formed therewith out of sheet metal, a pair of clips C³, of the knife blade type, preferably being provided in conjunction with the clip C' and another pair C⁴ 5 in conjunction with the clip C'', these knife blade clips being disposed near the base B¹⁶ at the ends of feet 183, branching laterally from a tongue 188 over which extends a strap 170 provided with a binding post P which serves as a terminal by 10 which the assembly can be included in the electrical circuit to be protected, in known fashion.

The reference characters P' and P'' indicate guides or clips for the conductors L' and L'' leading to the assembly from the two sides of the 15 working circuit.

In pursuance of the invention, an integrity indicator element I¹⁶, comprising an elongated body of insulating material having therein a suitable indicating means N visible through an orifice 107, is mounted as a bridge member upon a pair of standards U' and U'' of inverted U-shape 20 in end elevation, and the feet 185, 186 of which are formed as vertically disposed blades adapted to fit into the several clips C³ and C⁴ respectively, 25 as indicated, there being a pair of blades 185 on the member U', to enter the pair of clips C³, and a pair of blades 186 to enter the clips C⁴.

The U-shaped members U' and U'' accordingly constitute each a terminal for the indicator 30 means, the terminals of which, within the elongated body I¹⁶, are soldered, or otherwise suitably connected, to the medial portion of each U-shaped member, in well-known fashion, not illustrated 35 in detail.

It is clear from the above disclosure that the integrity indicator I¹⁶ will be included in shunt with the fuse cartridge F¹⁷ in the working electrical circuit when in operative position as shown in Figs. 17-19, and it will be understood that such 40 resistance for the indicator will be provided as only to permit passage of sufficient current to energize the indicating means and yield a signal through the orifice 107 when the fusible element in the fuse cartridge F¹⁷ shall have been fused by 45 the passage of a current of predetermined strength.

At any time, the integrity indicator I¹⁶ may be removed manually, having the fuse cartridge F¹⁷ in place, or both the indicator and the fuse 50 cartridge element may be removed by a single manual operation.

While the clips C³ and C⁴ may be of any suitable structure, it is to be noted that clips of the form illustrated, and best seen in Fig. 19, are preferred, each comprising a structure in which the upright parts 104 are struck up out of the body of the laterals 103, this constituting a very sturdy 55 clip structure.

Similarly it is preferred to form each terminal 60 strap 170 with a forked inner end, as indicated at 103, so that it can be tucked under the nut of the binding post P, and removed therefrom, while the leads L', L'' remain attached to the forked terminals.

In the modification shown in Figs. 20 and 21, the fuse cartridge element F²⁰ and the cooperating terminal clips C' and C'' may desirably be of known form, each of the clips having a forked strap 170, like that already described with respect 65 to Figs. 17-19 provided with a binding post P⁵ to facilitate rapid installation in the working circuit the latter being represented by leads L', L'' from sources of different potential.

The integrity indicator for this assembly may 75

comprise a device I of the type indicated by that reference character in Figs. 1 to 5 and described with reference thereto. The indicating means is provided with a stud terminal 33, as in the earlier 5 described structure, adapted to cooperate with the walls of a keyhole complementary aperture (see Fig. 21) in the bracket part 50 of a bracket B²⁰ bent from an upright post which has at its base a foot 166, suitably apertured to be transfixed by 10 one of the binding posts P⁵ having a nut P⁴ which acts to hold in assembled relation the extension 178 (see Fig. 21) from the clip C' of the fuse cartridge supporting structure, with the forked end of strap 177, and the said foot 166 15 of the bracket.

Upon loosening the nut P⁴, the bracket B²⁰ can be removed at any time, leaving the fuse cartridge F²⁰ in place, and similarly the fuse cartridge F²⁰ can be removed independently of the 20 integrity indicator.

As hereinbefore described the stud 33 of the indicating means I is in electrical connection with one terminal of the indicating lamp N', and the other terminal of the indicating lamp has an 25 insulated extension conductor 196 which is led along the base B, at one side of the fuse cartridge, to a clip C⁵ formed upon a strap S⁵ with an orifice through which extends the binding post P⁵ at that end of the cartridge fuse structure.

30 The indicating means, in this instance the lamp N', is thus included in a shunt around the fuse cartridge element F²⁰ and operates in known manner to signal the fusion of the fusible element (not shown) in the fuse cartridge element 35 F²⁰.

In pursuance of an important object of the present invention, as thus embodied, means are provided to permit the shunt conductor 196 to be adjusted to compensate for variations in the 40 length of the fuse cartridge intended to be used at F²⁰. For example, if a one-time type of cartridge fuse is used, as shown, the clips C' and C'' should be disposed at about the distance apart illustrated, and the conductor 196 need be no longer than shown in Fig. 21. It is, however, made of considerably greater length, in accordance with this feature of the invention, and the excess, or reserve length is coiled as shown at 196x, ready to be extended if required. An instance of 45 such desirable elongation would arise when a fuse cartridge is used of the type having as end terminals metal caps screwed upon nipples, to permit replacement of the confined fusible element when expended by fusion. Such fuses are somewhat longer than one-time fuses of like capacity, and of course one-time fuses of greater capacity are apt to be longer than those of relatively small capacity. Other reasons for variation in length 50 are common, and the provision made as illustrated in Figs. 20 and 21 constitutes this assembly what may be termed an all-purpose protective assembly of the type described, within limitations which will be readily understood by those skilled in the art.

60 An added feature of advantage in the structure shown in Figs. 20 and 21 is constituted by the telescoping protective tubular members M' and M'', the latter being snugly fitted to slide within the former, and each having smooth bores to pass 65 the conductor 196 freely and afford ample storage space for the helical reserve 196x.

This type of adjustable shunt can of course be applied to cartridge fuses of the knife-blade type, with but little need for alteration.

70 75 As another form of adjustable shunt, the draw-

ings illustrate in Fig. 22, a pair of links M³, M⁴, in the dotted portions of which is provided a binding bolt M, to hold the links together and keep them from lengthwise displacement when adjusted in length to compensate for the variations permissible in the length of any fuse cartridge which it may be desired to insert between the terminals T³ and T⁴.

The terminal T³ may be constituted by the foot 166 of a bracket such as that shown in Fig. 20 and described with reference thereto, this bracket being connected to one side of the indicator means I²², for example one terminal of a lamp. The other terminal of the lamp (not shown) has an extension conductor 116 which may be connected electrically to the shank M⁵ of link M³ in any suitable manner, as by soldering; while the link M⁴ has a shank M⁶ with a bend at M⁷ fitted into a clip M⁸ of the eye-shaped terminal member T⁴.

The mode of operation of this form of the shunt adjuster will be readily understood from the description of the preceding features of the present disclosure.

In Fig. 23, is shown a modified type of integrity 25 indicator element I²³ in assembly with a fuse cartridge element F²³ mounted in clips C²³ carried by a base B²³. In this form of embodiment of the present invention, the indicator I²³ is mounted in a pair of spring arms A, of which only 30 one is shown, it being understood that these arms are spaced apart suitably to receive the ends, as E', of an elongated body forming part of the indicator element, and upon which the indicating means is carried. The ends E' will preferably be of metal, and the arms A may be coiled to form clips Cx adapted to be constricted upon, and to form good mechanical and electrical contact with, the metal end terminals E' of the indicator element.

The arms A are suitably mounted on the base B²³, as by flanges c on an integral extension c' leading from the clip C²³, or by a strap connected thereto by the usual binding post P²³. This is a 45 very simple form of mount for the integrity indicator element and can be easily retracted manually to its dotted line position for the purpose of clearing the way for removal of the fuse cartridge F²³, while the integrity indicator is still retained in its mount.

The integrity indicator may also be removed independently of the fuse cartridge, and when the integrity indicator occupies its operative, full-line position to which it is biased by the arm A, it is well disposed for an attention-arresting display of its signal closely identified with the fuse cartridge F²³, of whose integrity or expenditure it is to witness visibly.

In Figs. 24 and 25 is illustrated a modification of what may be termed the swinging type of integrity indicator this modification comprising a hinged bracket part B⁶ hingedly mounted at 150 on an upright post 151, bent up from a sheet metal foot 156 which is suitably apertured to be held by a known form of binding post terminal P²⁴, the latter serving in the usual manner as one terminal by which the indicating means carried by the bracket part B⁶, as for example a neon discharge lamp N visible through an orifice n in the casing n', may be included in shunt with a 70 fuse cartridge element (not shown) in an electrical circuit to be protected.

It will be understood that an insulated conductor, as 152, leads from the other terminal of the indicating lamp, and that connection may 75

be made thereby to a terminal at the other end of the fuse cartridge structure, to complete the shunt, in substantially the manner hereinbefore taught.

- 5 The hinged bracket part B⁶ has a range of swinging movement limited by stops 153 and 154, the latter serving to define the operative position of the indicator shown in full lines, when it is disposed adjacent to the end of a fuse cartridge 10 element, indicated by the circle F²⁴ in schematic fashion, so that its signal, when given, will be identified with the adjacent fuse cartridge element, and when not energized its present will be an indication that the fuse element F²⁴ is intact. 15 A spring 155 serves to bias the bracket B⁶ to the operative full line position until it is swung back manually toward the dotted line position, and the spring tends to bias the indicator to the dotted line position as soon as the bracket swings 20 past the dead center of the spring's line of connection between hook 157 and eye 158.

The operator can thus release the indicator, after swinging it back, and it will still occupy the dotted position, swung back to clear the way 25 for the operator to work on the connections associated with the binding post P²⁴. Accordingly, the form of the invention just described is characterized by affording complete accessibility to all of the working parts of the protective assembly 30 of an integrity indicator element, a fuse cartridge element, and the supporting base with its circuit connections.

The indicator need never be disconnected, except for the substitution of a fuse indicating 35 means when one is expended, and in that event the studs 33 of the indicating means N are simply shifted out of the keyhole slots in bracket 50 as hereinbefore described, and a fresh one substituted in the manner known to the art.

40 Any suitable type of magazine indicator element may be utilized by suitable adaptation of the bracket 50, in any form of the invention forming the subject of this disclosure.

Although I have particularly described one particular physical embodiment of my invention and 45 explained the operation, construction and principle thereof, nevertheless I desire to have it understood that the form selected is merely illustrative, but does not exhaust the possible physical embodiments of the idea of means underlying my invention.

What I claim as new and desire to secure by Letters Patent of the United States, is:

1. In an integrity indicator device for a cartridge fuse, the combination, with a cartridge fuse element and a support therefor having terminals by which said fuse may be included in the electrical circuit to be protected, of an integrity indicator element including an indicating means 55 and means to support said indicating means fully exposed at or above the level of the cartridge fuse, in attention-arresting position and in electrical connection with said terminals, thereby to include said indicator means in a shunt with said 60 fuse in the working circuit, said device being characterized by having said fuse cartridge element removable while said indicating means remains in place and further characterized by having said integrity indicator element supported 65 by a support having a pair of bracket connectors 70

one at each end of said cartridge fuse element and including binding screws, and each having a foot with an open slot by which said foot can be fitted to one of the binding screw terminals on said support, one of said brackets having a bracket part with a keyhole slot formation to cooperate with a complementary stud-terminal provided on said integrity indicator means.

2. In an integrity indicator device for a cartridge fuse, the combination, with a cartridge fuse element and a support therefor having terminals by which said fuse may be included in the electrical circuit to be protected, of an integrity indicator element including an indicating means and means to support said indicating means fully exposed at or above the level of the cartridge fuse, in attention-arresting position and in electrical connection with said terminals, thereby to include said indicator means in a shunt with said fuse in the working circuit, said device being characterized by having said fuse cartridge element removable while said indicating means remains in place and further characterized by having a support for said indicating means supported by a support having a bracket at one end 15 of said cartridge fuse element and including binding screws and having a foot with an open slot by which said foot can be fitted to one of the binding screw terminals on said support, said bracket having a bracket part with a keyhole slot 20 formation to cooperate with a complementary stud-terminal provided on said integrity indicator element and another bracket adapted to be held by a terminal screw at the other end of said fuse element, said last-named bracket having an eye 25 and a slit to receive the bare end of a conductor leading from a terminal of said indicator means, whereby a shunt connection between said fuse terminals is completed, including said indicator means.

3. A supporting bracket-connector for a protective device of the class including a cartridge fuse element and an integrity indicator element, said bracket comprising a foot, an upright post and a bracket part formed with a pair of spaced 45 apart keyhole slot connector means adapted to complement a pair of terminal studs upon said integrity indicator element, said bracket being further characterized by having said foot formed with an open slot to permit ready attachment 50 with and detachment from, a binding screw constituting an electrical terminal for said elements in common.

4. A supporting bracket connector for a protective device of the class including a cartridge fuse element and an integrity indicator element, said bracket comprising a foot, an upright post and a bracket part formed with a pair of spaced 55 apart keyhole slot connector means adapted to complement a pair of terminal studs upon said integrity indicator element, said bracket being further characterized by having said foot formed with an open slot to permit ready attachment 60 with and detachment from, a binding screw constituting an electrical terminal for said elements in common and also by an orifice in said bracket part to permit access of a tool to said binding screw.

LYMAN E. DODGE.
